UNITED STATES PATENT OFFICE.

TRUE M. AVERY, OF GLENS FALLS, NEW YORK, ASSIGNOR TO ARROW-GRIP MANUFACTURING CO., INC., OF GLENS FALLS, NEW YORK, A CORPORATION OF NEW YORK.

ROLLER-BASE LIFTING JACK.

1,415,857.

Specification of Letters Patent. Patented May 16, 1922.

Application filed June 16, 1919. Serial No. 304,546.

To all whom it may concern:

Be it known that I, TRUE M. AVERY, a citizen of the United States, residing at Glens Falls, in the county of Warren and 5 State of New York, have invented new and useful Improvements in Roller-Base Lifting Jacks, of which the following is a specification.

This invention relates to improvements in 10 lifting jacks, proposing a construction especially useful in connection with work on automobiles and of the broad or general type which embodies roller supporting means movable relatively to the base and resilient 15 means acting on the roller supporting means and the base. In such type of construction the elements specified are so combined and arranged that the roller supporting means normally acts on the ground and the jack 20 and base derive their normal support from the roller supporting means and are normally held above or free from the ground, thus providing for the easy transportation or manipulation of the jack in placing the 25 same beneath the axle or other load to be lifted or while removing the same from the operating position, but permitting the base to move downward relative to the roller supporting means into positive and direct engagement with the ground when the load 30 is brought to bear upon the jack, the resilient means acting automatically to restore the roller supporting means to normal or jack-supporting position when the load 35 is relieved from the jack.

The principal objects of the invention, briefly stated, are to improve a jack of the type referred to in respect of compactness, 40 simplicity of structure, durability, strength, and manufacturing facility and economy.

With the above objects in view the invention consists in certain novel features of structure and arrangement appertaining to the mounting of the roller supporting means 45 and the resilient elements and to the form and details of the base as correlated to said rollers and elements. A jack in accordance with the invention is essentially characterized by vertically movable axles carrying 50 the roller supporting means, the construction of the base for stable engagement with the ground and with parts internally arranged to provide vertical guides for co-operation with the axles to prescribe their 55 movements as rectilinear and preferably to

center the springs by which the supporting rollers are normally projected, and means adjacent said guides against which the axles normally rest. These features and the details of structure and arrangement appurtenant thereto will be set forth at length as the description proceeds.

Embodiments of the invention are illustrated in the accompanying drawings, 60 wherein:

Figure 1 is a vertical longitudinal sectional view of a jack in which the features of the invention are incorporated, the construction here shown being preferred, as now considered.

Figure 2 is a detail vertical longitudinal sectional view of the upper element or cover of the base.

Figure 3 is an inverted plan view of the same.

Figure 4 is a plan view of the lower element or bottom of the base.

Figure 5 is a view part in side elevation and partly in vertical longitudinal section of the lower element or bottom of the base.

Figure 6 is a detail cross-sectional view on the line 6-6 of Figure 1.

Figure 7 is a vertical longitudinal sectional view showing an alternative construction of the base feature of the jack.

Figure 8 is a bottom plan view of the upper element or cover of the base shown in Figure 7.

Figure 9 is a plan view of the lower element or bottom of the base shown in Figure 7.

Similar characters of reference designate corresponding parts throughout the several views.

The jack proper may be of any suitable design and construction. As shown, it comprises an operating screw 1 working within an upright casing 2 and co-operating with a nut 3, which travels lengthwise of said casing and is formed at the lower end of a hollow column 4 into which the screw projects, 95 said column having at its upper end a supporting head 5 of suitable form for engagement with the axle or other object to be lifted. The screw 1 is rotatably mounted and carries at its lower end a bevel gear 6 100 which is driven by a bevel gear 7 on a shaft 8 journaled in a tubular bearing 9 formed as a lateral extension of the casing 2. The shaft 8 carries or is otherwise connected to a suitable operating handle (not shown). 110

The nut 3 is non-rotatable and co-operates with the casing 2 as a guide, said casing and nut preferably having conforming square cross-sections. As the screw 1 is turned in either direction the nut, and with it the head 5, is raised or lowered.

Referring to Figures 1 to 9:

The jack constructed as above described, or otherwise suitably, is combined with the 10 base and associated elements thereof which form the subject of the present invention. The base includes an upper member or cover 10 and, preferably, a lower member or bottom 11 secured in spaced relation to said 15 cover. The interior of the base is preferably completely enclosed and for this purpose one of its essential parts, in this instance the cover 10, is provided with vertical walls 12 delimiting a rectangular enclosure and 20 extending between the cover and bottom.

The jack is normally supported by roller supporting means, i. e. rollers 13, of which there are preferably four, these projecting below the base and, in the present embodiment, working through clearances 14 formed at the corners of the bottom 11. Where four rollers 13 are employed they are arranged in front and rear pairs; and the rollers of each 25 pair are mounted on an axle 15 disposed transversely of the base. Each axle 15 preferably has a square cross-section and is provided at its ends with reduced spindles 16 upon which the rollers are fitted, said spindles providing shoulders 17 at the ends of 30 the squared body of the axle and the rollers being confined between said shoulders and the adjacent walls 12.

The axles 15 are mounted for vertical movement within the base and are urged to 40 their lowest positions relative to the base by springs 33, two of which are preferably provided for each axle and are located somewhat near the ends thereof, said springs 45 preferably being of expansive spiral construction. The vertical movements of the axles 15 are positively prescribed by vertical guide lugs 18 and 19 provided at each end of the base, preferably in two groups or pairs, with a clearance 20 between the cooperating guide lugs of each pair; and the 50 axles 15 are arranged in the clearances 20, their fitting in said clearances being such as to permit the requisite freedom of their vertical movement but as to prevent any 55 sensible horizontal play. In the construction preferred the springs 33 are located between the co-operating guide lugs 18 and 19 which thus serve the additional function of controlling or aiding the action of said 60 springs.

In the present embodiment the bottom 11 provides a means against which the axles 15 normally rest, said axles being pressed against said bottom 11 by the springs 33 65 with the rollers 13 projecting below the base,

thereby enabling the easy transportation of the jack or its easy manipulation under the object to be lifted, the operating handle (not shown) preferably being used for such purposes. With the jack positioned for use, 70 when the head 5 engages the axle or other object and its upward movement relative to the casing 2 is continued, the first effect of such engagement will be to depress the base 75 relatively to the rollers 13 whereby the base 80 comes into direct engagement with the floor or ground. The base has secure and stable engagement with the floor or ground by means of its walls 12 and, preferably also of its bottom 11 and when said walls or bottom 85 or both engage the floor or ground, the supporting function is thereby transferred from the rollers 13 to the base, which latter insures the stability of the jack throughout the operation of the head 5 or so long as said 90 head bears the weight of the object to be lifted. When the object supported by the jack is to be restored to its normal position, the head 5 is lowered in the ordinary manner and when the normal support for such 95 object comes into operation so that the weight is taken from the head 5, the springs 33, during the continuance of the downward movement of said head, raise the jack relatively to the rollers 13 which are thus 100 once more projected below the bottom 11 and assume their normal jack-supporting function. The jack may thereupon be freely moved to some other position.

In the constructions disclosed the gear 6 100 is housed within the base and the screw 1 has a step bearing against the bottom 11, its bearing portion being centered in a collar 21 secured to said bottom. It is desirable that the enclosed working parts be protected 105 against any sensible accumulation of dust, and for this purpose the bottom 11 is imperforate, except for the clearances 14, and the lugs 18 adjoin the walls 12 at the ends of the base while the lugs 19 adjoin the walls 110 12 at the sides of the base, for this purpose being formed with transversely arranged extensions 22 which close the space between the transverse edges of the clearances 14 and the cover 10.

The features above described are common 115 to both of the constructions shown.

Referring to Figures 1 to 6:

In this, the preferred construction, the lugs 18 and 19 are secured to, preferably 120 cast with, the bottom 11 and strengthening ribs 23 extend between the lugs 19 and the collar 21. For the connection of the bottom 11, each wall 12 is provided on its inner face with a somewhat shallow centrally arranged 125 lug 24 whose lower longitudinal edge is rounded or beveled, as at 25, and the bottom 11 is provided, centrally of each of its four sides, with a raised lug 26 having a beveled or rounded upper longitudinal edge 27 130

and an underlying clearance 28. With the parts thus constructed the bottom is sprung into position within the walls 12, the rounded or beveled edges 25 and 27 enabling the 5 lugs 26 to be sprung past the lugs 24 and the latter projecting into the clearances 28 and engaging the lugs 26 from below with supporting effect, thereby firmly to sustain the bottom against the thrusts to which it is 10 subjected. The cover 10 may be provided with projections 29 which extend into the springs 33 and center them, the stability of said springs being further insured by their preferred location, as described, between 15 the cooperating lugs 18 and 19 and by the flatness and extent of the upper face or side of the axle 15 against which said springs bear.

Referring to the construction shown in 20 Figures 7 to 9:

In this construction the lugs 18 and 19 are secured to the cover 10 and the bottom 11 is secured in place against the lower faces 25 of said lugs by fastening screws 30 for which the lugs 19 may be provided with threaded recesses 31. For centering the springs 33 said cover is provided with sockets 32 in alignment with the clearances 20 between the cooperating lugs 18 and 19.

Having fully described my invention, I 30 claim:—

1. A lifting jack having a base provided with co-operating guide lugs and clearances between the guide lugs, axles fitted in the 35 clearances for vertical movement and each provided with roller supporting means, said base including a cover which encloses said lugs, axles and roller supporting means and also having means secured below said lugs 40 against which said axles may normally rest and springs acting within and on said cover and on said axles whereby to urge the latter downward relatively to said base, said roller supporting means normally projecting below 45 said base and the latter being formed for stable engagement with the ground or floor to assume the supporting function under the weight of the object supported by the jack.

2. A lifting jack having a base composed 50 of a cover and bottom connected together in spaced relation and as companion elements, pairs of co-operating guide lugs secured to one of said companion elements, each pair of 55 co-operating guide lugs having an intervening clearance, axles fitted in said clearances for vertical movement and each provided with roller supporting means, and springs acting on said axles to urge them downward 60 relatively to the base, said axles normally resting against said bottom and the latter having clearances through which the roller supporting means normally project, said base being formed for stable engagement with the 65 ground or floor to assume the supporting function with the ground or floor to assume the sup-

porting function under the weight of the object supported by the jack.

3. A lifting jack having a base provided with co-operating guide lugs and clearances between the guide lugs, axles of square 70 cross-section fitted in the clearances for vertical movement and each provided with roller supporting means, said base also having means secured below said lugs against which said axles may normally rest, expansive spiral springs fitted in said clearances above said axles and urging them downward relatively to said base, said roller supporting means normally projecting below said base and the latter being formed for stable 75 engagement with the ground or floor to assume the supporting function under the weight of the object supported by the jack.

4. A lifting jack having a base composed of a cover and bottom connected together in 80 spaced relation as companion elements and vertical walls extending between said elements, pairs of co-operating guide lugs secured to one of said companion elements, each pair of co-operating guide lugs having 85 an intervening clearance, axles fitted in said clearances for vertical movement and each provided with roller supporting means, and springs acting on said axles to urge them downward relatively to the base, said axles 90 normally resting against said bottom and the latter having clearances through which the roller supporting means normally projects, certain of said lugs being formed with extensions adjacent the clearances in said 95 bottom and between said companion elements to close the interior of said base, the latter being formed for stable engagement with the ground or floor to assume the supporting function under the weight of the object 100 supported by the jack.

5. A lifting jack having a base composed of a cover and bottom connected together in spaced relation as companion elements and vertical walls extending between said 110 elements, said bottom having corner clearances, supporting rollers normally operating through said clearances, transverse axles carrying said rollers, co-operating guide lugs between which the axles are fitted for vertical movement, and expansive spiral springs exerting thrust against the cover and the axles to urge the axles downward relatively to the base and into normal engagement with said bottom, said guide 115 lugs being arranged adjacent the respective edges of said clearances and also immediately adjacent the respective vertical walls which bound said clearances, said base being formed for stable engagement with the 120 ground or floor to assume the supporting function under the weight of the object supported by the jack.

6. A lifting jack having a base composed of a cover and bottom connected together in 130

- spaced relation as companion elements and vertical walls extending between said elements, said bottom having corner clearances, supporting rollers normally operating
- 5 through said clearances, transverse axles having reduced end spindles upon which said rollers are mounted, said spindles providing shoulders on said axles between which and the adjacent vertical walls said rollers
- 0 are confined, cooperating guide lugs between which the axles are fitted for vertical movement, and expansive spiral springs exerting thrust against the cover and the axles to urge the axles downward relative to the base and
- 5 into normal engagement with said bottom, said base being formed for stable engagement with the ground or floor to assume the supporting function under the weight of the object supported by the jack.
- 0 7. A lifting jack having a hollow base composed of a cover and bottom, said cover

having depending vertical walls within which said bottom is fitted and which are provided along their inner faces and adjacent their edges with shallow lugs 25 having rounded lower longitudinal edges, said bottom having along its edges raised lugs provided with rounded upper longitudinal edges and having clearances under said raised lugs in which the first-named 30 lugs engage when the bottom is sprung into position within said vertical walls, and operating parts arranged internally of said base and exerting thrusts on said bottom.

In testimony whereof I have hereunto set 35 my hand in presence of two subscribing witnesses.

TRUE M. AVERY.
